US0D1082048S

(12) **United States Design Patent** (10) **Patent No.:** **US D1,082,048 S**
(45) **Date of Patent:** **** Jul. 1, 2025**

(54) **MULTI TUBE CARRIER**

(71) Applicants: **STRATEC SE**, Birkenfeld (DE); **Instrumentation Laboratory Company**, Bedford, MA (US)

(72) Inventors: **Daniel Ahr**, Neuenburg (DE); **Thomas Lowien**, Pforzheim (DE); **Ralf Wolf**, Neuenburg (DE); **Christopher Almy, Jr.**, Bedford, MA (US); **Joshua A Shreve**, Bedford, MA (US); **Candice Bell**, Bedford, MA (US); **Benjamin E Newton**, Bedford, MA (US)

(73) Assignees: **STRATEC SE**, Birkenfeld (DE); **Instrumentation Laboratory**, Bedford, MA (US)

(**) Term: **15 Years**

(21) Appl. No.: **29/862,352**

(22) Filed: **Dec. 8, 2022**

(57) **CLAIM**

The ornamental design for a multi tube carrier, as shown and described.

DESCRIPTION

FIG. 1 is a perspective view of a multi tube carrier showing our new design;

FIG. 2 is a first side view thereof;

FIG. 3 is a second side view thereof;

FIG. 4 is a top view thereof;

FIG. 5 is a bottom view thereof;

FIG. 6 is a front view thereof; and,

FIG. 7 is a rear view thereof.

The broken lines depict portions of the multi tube carrier that form no part of the claimed design.
